UNITED STATES PATENT OFFICE.

FIORINDO DALLA COLETTA, OF ALFREDO CHAVES, OF RIO GRANDE DO SUL, BRAZIL.

DOUBLE-ACTING HYDRAULIC PUMP.

Application filed June 22, 1922. Serial No. 570,140.

To all whom it may concern:

Be it known that I, FIORINDO DALLA COLETTA, a citizen of Brazil, residing at Alfredo Chaves, State of Rio Grande do Sul, Brazil, have invented certain new and useful Improvements in Double-Acting Hydraulic Pumps; and I do hereby declare the following to be a full, clear, and exact description of the invention, such as will enable others skilled in the art to which it appertains to make and use the same.

My invention relates to improvements in semi rotary double-acting hydraulic pumps, in which the pistons are swung in arcs of circles through a limited angle on opposite sides of a common axis, and in which these pistons are provided with passages controlled by flap valves, the operation of which valves is facilitated and expedited by weighted arms, as will be hereinafter more fully described.

The invention provides a simple and efficient construction which is easily kept in order and requires a small amount of power to operate same, as well as other advantages that will be hereinafter more fully described.

The pump may be reciprocated either by a handle, or may be driven from the reciprocating part of any suitable engine, as may be preferred. For convenience of illustration I have shown the pump as provided with a handle for hand operation.

My invention will be more fully understood after reference to the accompanying drawings, in which like parts are indicated by similar reference symbols throughout the several views, and in which:—

Figure 1 is a front elevation of the pump with the valves in the neutral position.

Figure 2 shows a section along the line 2—2 of Fig. 1, and looking in the direction of the arrows.

Figure 3 shows the interior of the pump chamber with the front cover removed and at one end of the stroke, one of each set of valves being shown as open and the other closed.

Figure 4 shows the interior of the front cover as removed from the pump.

Figure 5 is a detail view showing the removable block containing the admission passage and the admission valves pivoted thereto.

Figure 6 is a detail view of the vibrating frame carrying the pistons, with the

weighted lever valves removed, and parts being broken away.

Figures 7 and 8 are detail views showing the oppositely disposed lever valves detached from the apparatus; and

Figure 9 shows a modified form of valve arrangement adapted to be mounted on the operating shaft.

The pump comprises a casing composed of two halves A and B, each preferably provided with lugs *a* and *b* connected together by the bolts C. The chamber A is provided with a journal bearing *a'* for the operating shaft D. The chamber B is provided with a gland B' for the said operating shaft which may be rocked either by a handle D', or in any other convenient way. The rear member of the casing A may be provided with suitable lugs *a''* for securing the pump to any suitable framework, not shown.

The two members of the casing are each provided with an annular groove, semi-circular in cross section, which when put together form a hollow annular chamber E which is separated by the partition F from the central chamber F', which central chamber has an opening *f* between the ends *f'* and *f''* of the partition F, as shown most clearly in Fig. 3.

The casing is provided at its lower end with an inlet opening G, and at its upper end with an outlet opening G', the outlet opening being connected by the flange *g'* to any suitable delivery pipe, not shown. The lower part of the casing is split to receive the stem *h* of the block H, provided with the inlet opening H^o, which opening branches in two directions *h'* and *h''* which are alternately closed by the flap valves I and I', which are pivoted to said blocks as at *i* and *i'*. This block H is provided with a flange *h''* for connecting same to a source of water supply, not shown.

In order to make a tight joint between the block H and the lower wall of the partition F, suitable packing J may be provided, as shown in Fig. 3. Secured on the operating shaft D I provide a frame for the pistons which, for convenience of construction, is shown as composed of two radial arms K, both fast on the shaft D, and carrying at their outer ends the pistons M and M' which are in the form of short tubes *m*, surrounded with a packing of leather or other suitable material *m'*. This packing is cupped as

shown in Fig. 6 so as to cause the piston heads to tighten on the up stroke and to move freely on the down stroke, thus making a tight joint, on the up stroke only.

5 The passages through the pistons are normally closed, respectively, by the valves n and n' which are carried by the levers N and N' , shown in Figs. 7 and 8, which are hinged, respectively, as at n^2 and n^3 , to their 10 respective pistons, and are provided with weighted arms n^4 and n^5 .

It will be seen that the arms N and N' and the valves n and n' , respectively, are reversely disposed, as shown in Figs. 3, 6 and 15 7. These arms are pivoted between the curved arms K' , and the inertia of the weighted ends cause the valves to operate more quickly, as will be hereinafter more fully described.

20 The vibratory movement of the shaft D may be limited by the radial arms K bringing up against the ends f' and f^2 , respectively, on the partition F , shown most clearly in Fig. 3.

25 One of the members of the casing, as B , may be provided with a priming hole b^3 for the insertion of the liquid in priming the pump, which may be closed by a suitable plug O and may also be provided with a 30 drain opening b^4 which may be closed by the draining plug O' . Instead of these plugs O and O' , suitable faucet arrangements may be used for filling and emptying the pump, as desired.

35 The operation of the device is as follows: Suppose the parts to be in the position shown in Fig. 1, with both the valves I and I' closed, fill up the pump chamber with water through the opening b^3 , and then close 40 the said opening; now if the shaft D be rocked to the right, as shown in Fig. 1, the valve I will be opened by suction, and the valve I' will be closed by pressure. In the same way the valves n will be closed by the 45 pressure of the liquid on one side, and the suction on the other, and the valve n' will be lifted by pressure of the water beneath the same; the parts then being shown in the position indicated in Fig. 3, when the liquid 50 is being sucked in past the valve I and is being delivered through the outlet G' .

The tendency of each weighted arm n^4 or n^5 , due to its inertia, will be to cause the corresponding valve to close quickly on the up stroke of the piston and to open quickly on the down stroke of the piston, so that a high degree of suction is secured when desired, and a quick flow of the escaping liquid on the delivery stroke of the pump is secured.

60 The result is that this automatic action of the weighted arms causes the pump to act at a high degree of efficiency, both in the suction secured and in the liquid delivered.

It will be obvious that the pump is double acting; that is, it delivers liquid and simul-

taneously sucks in fresh liquid at each vibration of the operating shaft. Where there is only a short lift, the pump itself will create a sufficient vacuum to lift the water, but where there is a longer lift, the pump 70 should be primed as stated.

Of course it is not within the capacity of any suction pump to lift fresh water more than approximately thirty (30) feet, or even less in practice. 75

Instead of the construction and operation of valves hereinbefore described, an anchor valve arrangement may be used, such as that shown in Fig. 9. It will be obvious that instead of flap valves, as shown, any suitable 80 form of valves, such as ball valves or the like, may be used, and I do not mean to limit the invention to any special form of valves, as other valves well known in the art may be employed. 85

It will be obvious that various other modifications might be made in the herein described construction, and in the combination and arrangement of parts which could be used without departing from the spirit 90 of my invention; and I do not mean to limit the invention to such details except as particularly pointed out in the claims.

Having thus described my invention what I claim and desire to secure by Letters Pat- 95 ent of the United States is:—

1. A double acting hydraulic pump comprising a casing provided with an annular chamber circular in cross section, and a central chamber with an annular rib cut away 100 throughout a segment of its upper portion separating the two chambers, the said casing being provided with an inlet opening and an outlet passage, a block provided with T-shaped passages therein projecting through the inlet opening of the casing, the said block being provided with oppositely disposed check valves controlling the inlet 105 passages therefrom, a shaft journaled transversely of said casing, a frame carried by said shaft and provided with curved oppositely disposed arms, perforated pistons carried by said arms adapted to fit in said annular chamber, valves carried by said pistons and adapted to open upwards, and means for rocking said shaft in reverse 110 directions.

2. A double acting hydraulic pump comprising a casing provided with an annular chamber circular in cross section, and a central chamber with an annular rib cut away 115 throughout a segment of its upper portion separating the two chambers, the said casing being provided with an inlet opening and an outlet passage, a block provided with T-shaped passages therein projecting through the inlet opening of the casing, the said block being provided with oppositely 120 disposed flap valves controlling the inlet 125 passages therefrom, a shaft journaled trans-

versely of said casing, a frame carried by said shaft and provided with curved oppositely disposed arms, perforated pistons carried by said arms adapted to fit in said annular chamber, flap valves carried by said pistons adapted to open upwards, and means for rocking said shaft in reverse directions.

3. A double acting hydraulic pump comprising a casing provided with an annular chamber circular in cross section, and a central chamber with an annular rib cut away throughout a segment of its upper portion separating the two chambers, the said casing being provided with an inlet opening and an outlet passage, a block provided with T-shaped passages therein projecting through the inlet opening of the casing, the said block being provided with oppositely disposed flap valves controlling the inlet passages therefrom, a shaft journaled transversely of said casing, a frame carried by said shaft and provided with curved oppositely disposed arms, perforated pistons carried by said arms adapted to fit in said annular chamber, oppositely disposed weighted levers pivoted to said pistons, flap valves carried by said levers and adapted to open upwards, and means for rocking said shaft in reverse directions.

25 to said pistons, valves carried by said levers

and adapted to open upwards, and means for rocking said shaft in reverse directions.

4. A double acting hydraulic pump comprising a casing provided with an annular chamber circular in cross section, and a central chamber with an annular rib cut away throughout a segment of its upper portion separating the two chambers, the said casing being provided with an inlet opening and an outlet passage, a block provided with T-shaped passages therein projecting through the inlet opening of the casing, the said block being provided with oppositely disposed flap valves controlling the inlet passages therefrom, a shaft journaled transversely of said casing, a frame carried by said shaft and provided with curved oppositely disposed arms, perforated pistons carried by said arms adapted to fit in said annular chamber, oppositely disposed weighted levers pivoted to said pistons, flap valves carried by said levers and adapted to open upwards, and means for rocking said shaft in reverse directions.

FIORINDO DALLA COLETTA.
